UNITED STATES PATENT OFFICE.

CHARLES H. AYARS, OF SALEM, NEW JERSEY, ASSIGNOR TO AYARS MACHINE COMPANY, OF SALEM, NEW JERSEY.

CAN-FILLING MACHINE.

Application filed May 6, 1922. Serial No. 558,868.

To all whom it may concern:

Be it known that I, CHARLES H. AYARS, a citizen of the United States, residing at Salem, in the county of Salem and State 5 of New Jersey, have invented certain new and useful Improvements in Can-Filling Machines, of which the following is a specification.

In Letters Patent of the United States 10 No. 1,073,067 granted me September 9, 1913, I have shown and described a can filling machine especially adapted for filling cans with liquid or semi-liquid materials in which there is a series of two chambered measuring shells, the chambers opening into each 15 other at the lower end; plungers adapted to reciprocate in each chamber; cam-tracks by which the plungers are reciprocated, and non-automatic means for displacing a selected section of one cam-track so that, if the 20 shaft which operates the rotating elements of the machine be revolved when there are no cams upon the can seats, the rollers which engage with the cam-track will follow a by-pass and leave one plunger in a 25 position which closes the outlet of the measuring shells so that the material will not be discharged when no can is in position to receive it, but is forced back into the 30 tank.

Automatic mechanism, for replacing the movable section of the cam-track, actuated by pressure exerted through the cams has been in use for some years. Such mechanism 35 is defective because the movable section of the cam-track is yieldingly held in alignment with the stationary section and when the positively driven roller engages with the movable section it exerts a force tending 40 to swing said section out of alignment with the stationary section and toward its non-engaging position. This force is transmitted to the positively held can and is often sufficient to dent or mar the can.

The object of this invention is to provide 45 automatic means for locking the track sections in alignment while the plunger operating roller is passing over the movable section and automatic means for releasing the 50 movable section from the domination of the lock while the roller is passing over the stationary section thereby preventing track displacement and providing against injury to cans by re-action of the force exerted by 55 the roller.

In the drawings:—

Figure 1 is a front elevation partly in section of a filling machine showing my invention applied thereto,

Figure 2 is a section taken on the line 60 2—2 of Figure 1,

Figure 3 is an enlarged side elevation of the invention illustrated in Figure 1,

Figure 4 is a view of the same general character as that shown in Figure 3, illustrating the invention in an operative position.

Figure 5 is an elevational view looking in the direction of the arrow X of Figure 4, and

Figure 6 is a top plan view of Figure 5.

Referring to the drawings, 10 represents part of the frame of the machine, 11 the tank from which the material to be canned is fed to the measuring shells, 12 a measuring shell consisting of two chambers, 13 and 14, communicating with each other through a port 15, the chamber 14 having a discharge nozzle 16 through which the material goes to the cans, 17 a plunger 70 mounted to reciprocate in chamber 13 and 18 a plunger mounted to reciprocate in chamber 14. The plunger 17 is carried by a rod 19 connected to a bracket 20 carried by a vertical rod 21 to which is secured a bracket 22 carrying a roller 23 adapted to travel on a cam track 24 and cause the plunger to reciprocate in its chamber. The plunger 18 is carried by a rod 25 connected to a bracket 26 carried by a rod 27 to which 75 is secured a bracket 28 carrying a roller 29 adapted to travel on a cam track 30 and cause the plunger to reciprocate in its chamber.

Cam track 30 is made in two sections 30 80 and 30^a, the latter being mounted that it may be swung in or out of alignment with the stationary section 30. The movable section is carried by a depending arm 35 supported by a lug 36 pivotally connected with 100 a lug 37 fixed to the frame. A spring 38, having one end attached to an arm 39 fixed to the frame and the other end attached to a lug 40 on the depending arm 35, serves to hold the movable section of the cam track 105 out of alignment with the stationary section as shown in Figures 1, 2 and 3. The lower end of the depending arm carries a bolt 41 taking through a link 42 which is pivotally attached at 43 to a lever arm 44 110

pivotedly mounted at 45 on a bracket 46 extending from the frame. This lever arm is normally held, by spring 38, in position to engage the cans as they reach their filling position as shown in Figure 2. Pressure of the can, as it is further rotated will force the lever arm, and consequently link 42 and arm 35, outwardly thereby forcing the movable section 30^a of the cam track into alignment with the stationary section 30. The roller 29 will then ride upon the track and plunger 18 will reciprocate in chamber 14. If there be no can in position to engage the lever arm 44 it will retain its position; the movable section of the cam track will be held out of alignment with the stationary section; the roller 29 will pass under the stationary section, and plunger 18 will be left at its low position closing the discharge outlet of the measuring cells.

When the positively driven roller engages with the movable section of the track it exerts a force tending to swing said section out of alignment with the stationary section and toward its non-engaging position. This force is transmitted through depending arm 35 and link 42 to the positively held can and is often sufficient to dent or mar the cans. To guard against such displacement of the movable section of the cam track and against such injury to the cans I provide the mechanism hereinafter described. The movable section is provided with a lug 47 adapted to engage with the outer side of the stationary section as the two are brought into alignment. A lever 48 preferably of the bell crank type has, at one end, a beveled face 49 of the latch type which extends into the path of travel of lug 47 and is spring held in a position adjacent to the outer side of the stationary section of the track so that as lug 47 approaches the stationary section it will depress the latch face, and as lug 47 contacts with the stationary section the latch will spring up and lock the lug and through it the movable section of track in aligned position.

The bell crank lever, as shown in Figures 5 and 6, is fulcrumed at 50 on a bracket 51 supported by the frame and the short end of the lever is pivoted at 52 to an upwardly extending link, 53, which at its upper end is pivotally connected by a bolt 54 with one end of an arm 55. This arm is carried by a sleeve 56 which is pivotally mounted on a bolt 57 carried by a bracket 58 secured to the frame. A shoe, or finger 59, also carried by sleeve 56, extends over the stationary section of the cam track and inclines downwardly into the path of travel of the roller 29. An arm 60 extending from bracket 51 is connected by a spring 61 with one end of the pivot bolt 54.

As a roller passes from the movable to the stationary section of the cam track the parts

will be in the position shown in full lines in Figure 5 with the latch face in engagement and holding the section in alignment. As the roller continues in its path of travel it engages with and lifts the shoe 59 thereby, through sleeve 56, lifting the outer end of the arm 55 which lifts link 53 and the short arm of the bell-crank lever, against the tension of spring 61, thereby withdrawing the latch from its locking position and positioning the parts as shown by dotted lines in Figure 5. When the roller passes from under the sleeve 59 the tension of spring 61 restores the bell crank lever to its normal position with the latch in position for again engaging with lug 47 as the movable section is swung into alignment.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a can filling machine, a cam track having a stationary and a movable section normally held out of alignment with the stationary section; a lever arm adapted to be engaged by a can as it reaches its filling position; connections between the lever arm and the movable section of the cam track whereby movement of the can swings the movable section into alignment with the stationary section and a yieldingly mounted latch adapted to engage with the movable section when it reaches its aligned position and hold it in alignment.

2. In a can filling machine, a cam track having a stationary and a movable section normally held out of alignment with the stationary section; a lever arm adapted to be engaged by a can as it reaches its filling position; connections between the lever arm and the movable section of the cam track whereby movement of the can swings the movable section into alignment with the stationary section; automatic means for locking the sections in alignment, and automatic means for releasing the lock.

3. In a can filling machine, a cam track having a stationary section and a movable section normally held out of alignment with the stationary section; means for automatically swinging the movable section into alignment with the stationary section; a roller adapted to travel on the track; a spring pressed latch adapted to engage with the movable section as it reaches its position of alignment and lock it in alignment, and

means actuated by the roller for releasing the lock.

4. In a can filling machine, a cam track having a stationary section and a movable section normally held out of alignment with the stationary section; means for automatically swinging the movable section into alignment with the stationary section; a roller adapted to travel on the track; a spring pressed latch adapted to lock the movable section in alignment; a pivotally mounted shoe extending into the path of the roller and connections between the shoe and the latch whereby as the shoe is lifted by the roller the latch is disengaged.

5. In a can filling machine, a cam track having a stationary section and a movable section normally held out of alignment with the stationary section; means for auto-

matically swinging the movable section into alignment with the stationary section; a roller adapted to travel on the track; a lever carrying at one end a latch part adapted to lock the movable section in alignment; an arm pivotally mounted on a fixed part of the frame; a link pivotally connecting the lever and the arm; a spring normally holding the lever in its locking position, and a shoe adapted to lift the arm and to be lifted by the roller thereby disengaging the lock.

In testimony whereof I have signed my name to this specification in the presence of two subscribing witnesses.

CHARLES H. AYARS.
